A. J. PERKINS ET AL

LIFTING JACK FOR AUTOMOBILES

Filed July 2, 1923

Fig. 1.

UNITED STATES PATENT OFFICE.

ANDREW J. PERKINS AND LESTER PERKINS, OF CHICAGO, ILLINOIS, ASSIGNORS TO
YELLOW JACK-IT MANUFACTURING COMPANY, A CORPORATION OF ILLINOIS.

LIFTING JACK FOR AUTOMOBILES.

Application filed July 2, 1923. Serial No. 648,885.

This invention relates to lifting jacks and more particularly to portable jacks designed for use in connection with the lifting of automobiles and other heavy vehicles.

5 One of the objects of the present invention is to provide an improved portable jack so constructed that the same can be quickly adjusted to the proper height of the axle of the vehicle without any great effort on the 10 part of the operator.

A further object of the invention is to provide a simple and economical frame construction of a lifting jack which can be quickly and readily assembled.

15 A further object of the invention is to provide an easily manipulated foot lever mechanism within easy reach of the operator for raising and lowering the extensible member.

20 A still further object of the invention is to provide a lever mechanism adapted to co-operate in connection with a gravity actuated pawl which locks the extensible member in predetermined positions of adjustment.

25 These and other objects are obtained by providing a construction and arrangement of the various parts in the manner herein-after described and particularly pointed out 30 in the appended claims.

One embodiment of the invention is illustrated in the accompanying drawings and in these drawings Fig. 1 is a top plan view of the lifting jack showing our improvement embodied therein.

35 Fig. 2 is a side elevational view showing the manner in which our improved foot lever mechanism operates the gravity actuated pawl for adjusting the extensible member.

40 Fig. 3 is a side elevational view of the lifting jack on the side opposite to that shown in Fig. 2 and shows the foot lever mechanism for lifting the extensible member.

45 Fig. 4 is a cross sectional view of the lifting member showing the manner in which the gravity actuated pawl mechanism is adapted to engage the extensible member 50 in locking the same in various positions of adjustment, and

55 Fig. 5 is a cross sectional view taken on the lines 5—5 in Fig. 1 showing the manner

in which the guide members secured to the foot lever mechanism engage the longitudinal main frame members. 55

As illustrated in the drawings our improved lifting jack comprises a pair of parallel longitudinally extending main frame members 10, preferably constructed of flat 60 steel bars which are secured together by a series of bolts 12, suitable sleeves 13 being carried by these bolts for spacing these frame members from each other. Secured to the rear end of the longitudinal main frame 65 members 10 at the outer sides thereof are two angular members 14. Secured to the angle members 14 by means of the U bolts 15 is an axle 16. Rotatably mounted on the axle 16 are the usual carrying truck wheels 70 17 held in position by the usual washers and cotter pins 18. Adjustably mounted adjacent the truck carrying wheels 17 and between the guide plates 19 secured to the inner sides of the longitudinal frame members 10 is the usual lifting member 20. The lifting member 20 is provided with two rollers 21 journaled on the lower end thereof 75 which engage with the flexible member 22 in a manner to be adjusted thereby between 80 the guide members 19. The rear end of the flexible member 22 extends beneath the rollers 21 and has its rear end thereof connected to the main frame, not shown, while the forward portion of the flexible member 22 85 extends upwardly as shown at 23 and passes over a roller 24 journaled on a bolt 25 secured to the main frame members 10. The forward end of the flexible member 22 is secured to an ear 26 formed integrally with 90 a winding drum 27. The drum 27 has formed integrally therewith a ratchet wheel 28 which is adapted to be engaged by a pawl 29 pivoted at 30 to one of the frame members 10. From this construction it will 95 be seen that as the winding drum 27 is rotated the flexible member 22 is adapted to be wound or unwound as the case may be and the pawl 29 is actuated to lock the drum in various positions of adjustment. The 100 winding drum 27 is actuated by a lever 31 pivoted on a shaft 32. The shaft 32 is journaled on the forward ends of the main frame members 10 and also forms an axis for the winding drum 27. The lever 31 105 is provided with a pawl 33 pivoted at 34

and adapted to engage the ratchet wheel 28. Both the pawls 29 and 33 are provided with suitable connections which extend up to and are within easy reach of the hand 5 of the operator by means of which either of these pawls may be actuated for disengaging the same from the ratchet wheel 28. It will be further understood that spring actuating means are provided for normally 10 locking or forcing these pawls into engagement with the ratchet teeth. The construction thus far described forms no part of the present invention and accordingly a more detailed description of the same is not necessary. 15

In connection with our improved frame construction of a lifting jack we have provided a novel arrangement by means of which the front caster wheel brackets are 20 secured to the main frame and the bolts for securing these brackets form the pivots for the levers for operating and adjusting the extensible member. This construction comprises two caster brackets 35 secured to the 25 outer sides of the frame members 10 and provided with caster wheels and supports 36. Positioned between the main frame members 10 and in transverse alignment with the caster brackets 35 is a spacer member 37. The spacer member 37 together with the 30 caster brackets 35 are provided with registering apertures which extend through the main frame 10. Through these apertures the bolts 38 and 39 extend for securing the 35 caster brackets 35 as well as the spacer member 37 together. The bolt 38 extends through one of the brackets 35 in a manner to form a pivotal bearing for the foot lever 40, as shown at 41. The foot lever 40 extends rearwardly and is twisted in a manner to present its flat side in the form of a foot treadle 40 as shown at 42 by means of which the lever is actuated. The lever 40 is bent around the 45 caster bracket 35 as shown at 43 and is then bent at 44 where it extends along parallel with the main frame 10. The free end of the lever 40 is adapted to engage the extensible member in the manner hereinafter described.

50 Positioned on the side opposite the lever 40 is a second lever 45 which is pivoted at 46 to an extension of the bolt 39. The lever 45 is formed in a manner similar to the lever 40 in that it conforms to the shape 55 of the side of the jack, and the rearward end of the same is formed parallel to the main frame member 10. The forward end of the lever 45 is provided with a foot treadle portion 47, while the rear end of the lever is provided with a horizontally disposed flat 60 portion 48 twisted at right angles with respect to the body portion of the lever and is adapted to engage the gravity actuated pawl in the manner hereinafter described. 65 Each of the levers 40 and 45 are provided

with guiding members 49 secured by means of bolts 50. These guiding members are secured to the outer sides of these levers and extend upwardly in the form of a loop and extend over and downwardly as shown at 70 51, in Fig. 5, in a manner to engage the inner sides of the frame members 10. From this construction it will be seen that each of the levers are free to be actuated in a vertical plane and are held against lateral 75 movement or displacement by the guiding members 49 having their inner portions 51 engaging the main frame members 10.

Adjustably mounted in the lifting member 20 is the usual extensible member 52 provided with a pivotal cradle 53 of suitable form, which is adapted to engage the axle of the vehicle. The extensible member 52 is provided with a laterally extending lug 54 having an enlarged head on the outer end 85 thereof as shown at 55. The lug 54 is adapted to be engaged by the lever 40 when the extensible member 52 is adjusted by the operator when the foot treadle portion 42 of the lever 40 is depressed. The extensible member 52 is further provided with a plurality of ratchet teeth 56 formed on the rear side thereof, which in turn are adapted to be engaged by a gravity actuated pawl 57. The pawl 57 is pivotally mounted in a socket 58 formed by a bracket 59 secured to a lug 60 of the lifting member 20. The pawl 57 is provided with a normally vertical shank portion 61 which extends into the socket and is held from displacement therein by two horizontally disposed bolts or pins 62. The gravity pawl is actuated or pressed into engagement with the ratchet teeth 56 of the extensible member 52 by a weighted arm 90 extending laterally from the pawl at 63 and having a forwardly extending portion 64 which terminates in a ball or weight 65. The ball or weight 65 normally actuates the pawl into engagement with the teeth and is positioned over the horizontally disposed flat portion 48 of the lever 45 in a manner to be engaged or lifted by this portion 48 when the foot treadle 47 of the lever 45 is depressed by the operator to disengage the pawl from the ratchet teeth of the extensible member. 100

It will be seen from the above description that a very simple and efficient construction of a lifting jack mechanism for adjusting the extensible member has been provided and one in which the operating levers are positioned on the opposite sides of the jack within easy reach of the operator where they can be manipulated to adjust the extensible member to various positions of adjustment. 110

What we claim as our invention and desire to secure by Letters Patent is:—

1. A lifting jack comprising a frame, a lifting member mounted on said frame, an extensible member adjustably mounted on 120

130

5 said lifting member, a pawl mounted on said lifting member for engaging and supporting said extensible member in various positions of adjustment, and a lever pivoted to said frame and engageable with said pawl for disengaging said pawl from said extensible member in all positions of adjustment of said lifting member.

10 2. A lifting jack comprising a frame, a lifting member mounted on said frame, an extensible member carried by said lifting member, a pawl pivotally mounted on said lifting member and engageable with said extensible member, said pawl having an 15 arm extending forwardly of its pivot, and a lever pivoted to said frame and engageable with said arm in all positions of adjustment of said lifting member for disengaging said pawl from said extensible 20 member.

25 3. A lifting jack comprising a frame, a lifting member mounted on said frame, an extensible member carried by said lifting member, a pawl pivotally mounted on said lifting member and engageable with said extensible member, a weighted arm formed integrally with said pawl and extending forwardly with respect thereto, and a lever pivoted to said frame and engageable 30 with the lower side of said pawl for disengaging said pawl from said extensible member.

35 4. A lifting jack comprising a frame, a lifting member mounted on said frame, an extensible member carried by said lifting member, a plurality of teeth formed on the rear side of said extensible member, a pawl pivoted to said lifting member and engageable with the teeth on said extensible member, a weighted arm formed integrally with and extending laterally and forwardly from said pawl for normally actuating said pawl into engagement with said teeth, and a lever pivoted to said 40 frame and engageable with said arm for

disengaging said pawl from the teeth on said extensible member.

5. A lifting jack comprising a frame, a lifting member mounted on said frame, an extensible member carried by said lifting member, a pawl carried by said lifting member and engageable with said extensible member for adjustably supporting said extensible member, a lever pivoted to said frame and engageable with said pawl, and means secured to said lever and engageable with said frame for guiding said lever in its movement on said frame.

10 6. A lifting jack comprising a plurality of longitudinally extending frame members, lifting and extension mechanism positioned between said members, a pair of carrying wheels supporting the rear end of said frame, caster brackets secured to the outside of said frame members, caster 15 wheels mounted in said caster brackets for supporting the forward end of said frame, levers pivoted to said caster brackets for adjusting said extension mechanism, and means for securing said caster brackets to 20 said frame and forming the pivots for said levers.

25 7. A lifting jack comprising a plurality of longitudinally extending frame members, lifting and extension mechanism 25 slidably positioned between said members, supporting wheels for the rear end of said lifting jack, caster brackets secured to the outside of said frame members, caster 30 wheels mounted in said brackets for supporting the forward end of said jack, levers for adjusting the said extension mechanism, and bolts for securing said caster brackets to said frame and forming the 35 pivots for said levers.

40 In testimony whereof we have signed our names to this specification, on this 19th day of June, A. D. 1923.

45 LESTER PERKINS.
ANDREW J. PERKINS.
